UNITED STATES PATENT OFFICE

HERBERT S. ROYLE, OF PHILADELPHIA, PENNSYLVANIA

DESIGN FOR A TEXTILE FABRIC

Application filed August 16, 1930. Serial No. 36,685. Term of patent 3½ years.

To all whom it may concern:

Be it known that I, HERBERT S. ROYLE, citizen of the United States, residing at 5015 Akron St., Philadelphia, in the county of Philadelphia and State of Pennsylvania, have invented a new, original, and ornamental Design for Textile Fabric, as shown in the accompanying drawing, and described in the following specification.

In the accompanying drawing, the figure represents a top plan view of a section of textile fabric embodying my new and original design somewhat reduced in size, the dot and dash lines indicating the area of the repeat unit.

I claim:

The ornamental design for textile fabric as shown and described.

HERBERT S. ROYLE.
